UNITED STATES PATENT OFFICE

JOHN K. MABBS, OF BAYSIDE, NEW YORK, ASSIGNOR TO OXWELD ACETYLENE CO., OF NEW YORK, N. Y., A CORPORATION OF WEST VIRGINIA

DESIGN FOR A HEAD FOR DETECTORS OF COMBUSTIBLE GASES

Application filed August 29, 1929. Serial No. 32,600. Term of patent 14 years.

To all whom it may concern:

Be it known that I, JOHN K. MABBS, a citizen of the United States, residing at Bayside, in the county of Queens and the State of New York, have invented a new, original, and ornamental Design for a Head for Detectors of Combustible Gases, of which the following is a specification, reference being had to the accompanying drawings, forming a part thereof.

The drawings are perspective views of a detector head illustrating my new design, Figure 1 showing the handle inclined slightly

forward with the clip in profile, and Figure 2 showing the handle inclined slightly rearward, with the ribs on the handle in a horizontal plane.

I claim:

The ornamental design for a head for detectors of combustible gases substantially as shown.

In witness whereof I have hereto affixed my signature this 15th day of August, 1929, at New York, N. Y.

JOHN K. MABBS.
